Attorney

UNITED STATES PATENT OFFICE.

ARCHIE CLAWSON, OF ROCKVALE, MONTANA.

FOLDING BOX.

1,277,547.

Specification of Letters Patent.

Patented Sept. 3, 1918.

Application filed December 12, 1917. Serial No. 206,810.

To all whom it may concern:

Be it known that I, ARCHIE CLAWSON, a citizen of the United States, residing at Rockvale, in the county of Carbon and State 5 of Montana, have invented certain new and useful Improvements in Folding Boxes, of which the following is a specification, reference being had to the accompanying drawings.

10 This invention relates to certain new and useful improvements in folding boxes or receptacles and more particularly to a device of the character shown and described in my prior application for patent filed April 7, 15 1917, Serial No. 160,442.

It is the primary object of the present invention to provide very simple and effective means for sustaining the side and end sections of the box or receptacle in their 20 upright or vertical positions.

It is a more particular object of the invention to provide a corner plate for the sides of the box which is fixed to the ends thereof at their upper edges, each of the corner 25 plates having an arm struck therefrom fitted in a recess in the upper edge of the side wall of the box, and a swinging hook mounted in said arm to operatively engage in a notch or recess in the upper edge of the end wall 30 of the box.

It is a further general object of my invention to improve the construction disclosed in my prior application in the particulars above noted whereby the manufacturing cost of the 35 article may be reduced, and its durability, serviceability and convenience in practical use greatly enhanced.

With the above and other objects in view, the invention consists in the improved construction, combination and arrangement of the several parts, as will be hereinafter more fully described, subsequently claimed, and illustrated in the accompanying drawings in which similar reference characters designate 45 corresponding parts throughout the several views and wherein,

Figure 1 is a side elevation of a box or receptacle having my invention applied thereto;

50 Fig. 2 is an enlarged sectional view taken on the line 2-2 of Fig. 1;

Fig. 3 is a top plan view the top of the

box being removed and Fig. 4 is a perspective view of one of the corner plates.

Referring in detail to the drawing S 55 designates the side wall of the box, crate or other structure, E the end wall thereof and T the removable top. The side and end walls of the box structure may be mounted upon the bottom of the box as disclosed in 60 my prior application above referred to, or in any other suitable manner.

To each side of the box or receptacle at the ends thereof and at its upper edge, the corner plates generally designated by the 65 numeral 5 are riveted or otherwise securely fixed. These corner plates are formed of sheet metal, and each plate is bent to provide the portions 6 and 7 extending at right angles with respect to each other. The portion 6 of the corner plate is fixed to the outer side face of the side wall S of the box while the other portion 7 of the corner plate extends around the end edge of said side wall and inwardly therefrom. The upper portions of the parts 6 and 7 of the corner plate project above the plane of the upper edge of the side wall S and the portion 6 is provided with a horizontally extending elongated opening 8 for a purpose which will be 70 presently stated. An arm 9 is struck out from the portion 6 of the corner plate below the opening 8 therein and extends inwardly, at right angles to the plate. The extremity of this arm is turned or bent upon 75 itself to provide a sleeve 10 in which the angular end 12 of a rod 11 is loosely engaged. This rod at its other end is provided with a relatively long angularly disposed end portion 13 the extremity of which 80 is disposed in contiguous relation to the inner face of the portion 7 of the corner plate. This end 13 of the rod 12 is adapted to engage in a notch or recess e in the end wall E of the box or crate structure.

In the arrangement of the parts of the box in their erect positions, the end walls are first moved to a vertical position upon the bottom of the box, and the side walls are then moved upwardly and inwardly, it being understood that the rods 11 are first disposed in the position shown in dotted lines in Fig. 2 of the drawing. When the side walls are brought to their erect posi-

tions, the portions 7 of the corner plates engage upon the outer face of the end walls. The rods 12 are then swung inwardly and downwardly to engage in the notches *e* in 5 the upper edges of the end walls. Thus the side walls will be securely held in their erect positions. The arms 9 are seated in mortises or recesses indicated at *s* in the upper edges of the side walls of the box so 10 that the arms will be flush therewith. When the top *T* of the box is arranged in place between the upwardly projecting portions of the corner plates and upon the side and end walls it will be manifest that the free 15 ends of the rods 11 are securely retained in the notches in the end walls.

The means for securing the top of the box in position, is quite similar to that shown and described in my pending application for 20 patent filed May 21, 1917, Serial No. 169,979. This securing means for the box top consists in a bar 14 which is slidably mounted upon the top of the box and is held in place by the spaced guide straps indicated at 15. 25 One end of this bar is formed with a downwardly projecting hook 16, while the other or inner end of the bar is provided with an upwardly projecting flange 17. To the under side of the bar 14 one end of a leaf 30 spring 18 is fixed and to the other end of this spring a pin 19 is suitably secured, said spring projecting upwardly through an opening 20 in the bar 14. The box top immediately beneath the bar 14 is suitably recessed to accommodate the leaf spring 18.

In the operation of the device for securing the box top in position, when the top *T* is arranged upon the upper edges of the side and end walls of the structure, the pin 20 is 40 first depressed and the bar 15 is forced outwardly to project the hook 16 thereon to a point in spaced relation to the edge of the top, the pin 20 moving beneath one of the straps 15. This movement of the bar is limited by the engagement of the end flange 17 thereon with the other strap 15. After 45 the box top is arranged in place the bar 14 is moved inwardly on the box top to engage the hook 16 in the opening 8 of the corner plate. When in this position, the leaf spring 18 will project the pin 19 upwardly through the opening 20 at a point contiguous to the strap 15. Thus the pin will act as a stop against said strap to prevent the casual outward shifting movement of the bar 15.

From the foregoing description taken in connection with the accompanying drawing, the construction, manner of operation and several advantages of my invention will be 60 fully and clearly understood. The device as a whole is quite simple in its construction, and may be easily and quickly operated to secure the several parts of the box structure in their erect positions. By providing the 65 swinging hooks 11 upon the corner plates,

much time and labor may be saved in the assemblage and arrangement of the several parts in the manufacture of the box, while at the same time possibility of loosening or displacement of the swinging hooks or rods 70 is obviated. The present improvements also provide a very desirable and serviceable device, without materially increasing the manufacturing cost of my original box structure.

75 While I have herein shown and described the present construction and arrangement of the several parts, it is to be understood that the device is susceptible of considerable modifications and I therefore reserve the privilege of adopting all such legitimate changes as may be fairly embodied within the spirit and scope of the invention as claimed.

85 What I claim is:

1. The combination with a box structure having foldable side and end walls, of a plate fixed to one of said walls and having an angular arm countersunk in the edge of said wall, said arm being of a length substantially equivalent to the thickness of the box wall, and a latch element loosely engaged at one of its ends in the extremity of said arm and adapted for engagement at its other end with a contiguous wall of 95 the box structure to retain the box walls in their erect positions.

90 2. The combination with a box structure having foldable side and end walls, of corner plates secured to the upper edges of the side walls at their opposite ends, each corner plate having an arm projecting inwardly over the edge of the side wall, and a latch element swingingly mounted in said arm to coat with the adjacent end wall of 100 the box whereby said walls are retained in their erect positions.

105 3. The combination with a box structure having foldable side and end walls, of corner plates secured to the upper edges of the side walls at their opposite ends, each corner plate having an arm thereon projecting inwardly over the edge of the side wall of the box, and an angular rod having one end loosely mounted in said arm and adapted for engagement at its other end with the end wall of the box structure to retain said side and end walls in their erect positions.

110 4. The combination with a box structure having foldable side and end walls, of corner plates secured to the upper edges of the side walls at their opposite ends, each corner plate having an arm thereon projecting inwardly over the edge of the side wall of the box, and an angular rod having one end loosely mounted in said arm, the end wall of 115 the box being provided in its upper edge with a notch adapted to receive the other end of said rod whereby the side and end walls are held in their erect positions.

5. The combination with a box structure having foldable side and end walls, of corner plates secured to the upper edges of the side walls at their opposite ends, each corner 5 plate having an arm struck therefrom and extending at right angles to the plate, the edge of the side wall being mortised to receive said arm, and a latch rod swingingly mounted in the end of said arm and adapt-

ed for engagement with the end wall of the 10 box to retain the end and side walls in their erect positions.

In testimony whereof I hereunto affix my signature in the presence of two witnesses.

ARCHIE CLAWSON.
